UNITED STATES PATENT OFFICE.

THIERON L. HILES, OF CHICAGO, ILLINOIS.

HEADLIGHT.

No. 818,151.

Specification of Letters Patent.

Patented April 13, 1909.

Application filed January 2, 1909. Serial No. 470,417.

To all whom it may concern:

Be it known that I, THIERON L. HILES, a citizen of the United States, and resident of Chicago, in the county of Cook and State of Illinois, have invented certain new and useful Improvements in Headlights; and I do hereby declare that the following description of my said invention, taken in connection with the accompanying sheets of drawings, forms a full, clear, and exact specification, which will enable others skilled in the art to which it appertains to make and use the same.

This invention has general reference to improvements in headlights for automobiles, launches, locomotives, ships, and other vehicles and vessels; and it consists, essentially, in the novel and peculiar combination of parts and details of construction, as herein-after first fully set forth and described, and then pointed out in the claims.

In the drawings already mentioned, which serve to illustrate this invention more fully, Figure 1 is a longitudinal sectional elevation of my improved headlight as used in connection with a gas burner. Fig. 2 is an elevation of fragment of the said headlight showing details of construction of the adjusting mechanism. Fig. 3 is a perspective view of the tapering adjusting block located on the outside of the shell or casing of this lamp. Fig. 4 is a plan of the reinforcing-plate located within the said shell, and Fig. 5 is a perspective view of the adjusting mechanism employed for bringing the source of light into the exact focus of the reflector. Fig. 6 is a longitudinal sectional elevation of this headlight as used in connection with an electric incandescent lamp. Fig. 7 is a side-elevation of the adjusting mechanism adapted for use in connection with an incandescent electric lamp.

Like parts are designated by corresponding symbols of reference in all the figures.

45 The object of this invention is the production of an efficient, serviceable, and convenient headlight for automobile and other purposes, in which a parabolic reflector is employed in connection with either an electric incandescent lamp or a gas-burner. To accomplish this object, I proceed, as follows:

50 In the drawings designates the outer casing of this headlight. It is, preferably, circular in transverse section and tapering longitudinally, and for the purpose of stiffening this casing, I prefer to corrugate the

same, as clearly illustrated in the figures. The forward, larger, end of this casing is closed by a door 11, having a glass-front 12, which glass front is held in position in the door-frame by a split-ring 13, engaging an outwardly-projecting bead 14, by being sprung into the annular groove formed by said bead. This door is hinged to the casing 10, and locked thereto by a catch or similar contrivance, not shown, in any desired manner.

The rear end of the casing 10 is closed by a bottom 20, which is removably held in the casing by screws 43 or other convenient means. Within this casing there is located a parabolic reflector 15, which has at its open end an outwardly-flaring flange 16, and it is held centrally within the casing by a ring 18, removably secured to the casing by screws 42. The ring has an annular groove 19, which engages the flaring flange on the reflector, an elastic packing of felt, asbestos, or similar material being placed in this groove and surrounding the flange to prevent rattling and also breakage of the reflector. The rear end of this reflector is sustained in the casing by a diaphragm 21, having an outwardly-flaring flange 22, engaging the curved back of said reflector, an elastic ring or packing 23, being interposed between said flange 22 and the back of the reflector for the same purpose as the packing 23 at the forward end of the reflector.

The device thus far described is illustrated in Fig. 1, but where cheapness of construction is a desideratum, I may dispense with the diaphragm 21 and form in the bottom 20 a flaring member 22, as shown in Fig. 6; a space 57, behind the reflector 15 being provided to protect the latter from injury or breakage.

42 is a source of light, being either a filament of an electric, incandescent, lamp, or a gas or acetylene-gas burner. It is surrounded by a glass protector 36, which in the case of an incandescent electric lamp is its glass bulb; but in the event of a gas burner being used, it is a glass chimney, as illustrated in Fig. 1, said glass protector being employed to prevent heat from affecting the reflector. This source of light is mounted upon a socket 27, and the latter secured to a tubular member 26, which member is screw-threaded at its upper end for this purpose. The lower end of this tubular member is also screw-threaded to engage an exteriorly screw-

threaded sleeve 44, Figs. 6, and 7, said sleeve being in screw-threaded engagement with a slidably-arranged block 28, having an upwardly-projecting, internally-screwed threaded boss 29, for this purpose, said block 28 being located within the casing 10.

31 is a reinforcing plate permanently secured to the inner surface of the casing 10 over a slotted aperture 25 therein, to strengthen the casing at this point.

33 is a fixed block having an oblong aperture 35, surrounded by upwardly-projecting ledges 34, by which it engages the slotted aperture 25 in the casing and also a portion 15 of the slotted aperture 32 in the reinforcing plate 31; said blocks 28 and 33 being of wedge-shape or tapering contour to enable the source of light to stand perpendicular in reflector 15. The tubular member 26 passes 20 through the sleeve 44, the reinforcing-plate 31, and the upper block 28, and it has at its lower end lock-nuts 41 for the object which will hereinafter more fully appear.

56 are the electric conductors or flexible 25 cords by which the current is conveyed to the filament through the connecting socket 27. These conductors are passed through the tubular member 26 as illustrated in Fig. 6, and terminate in the socket 27 in the usual 30 manner.

I shall now proceed to describe how the adjusting mechanism is manipulated in order to bring the source of light 42 into the exact focal point of the parabolic reflector.

35 The tubular member 26, carrying at its upper end the source of light passes through the sleeve 44 and it has a lock-nut 45 below the fixed block 33. By slackening this lock-nut the sliding block 28 is free to move forwardly or backwardly within the slotted aperture 32 of the reinforcing plate 31 to secure the horizontal adjustment of the source of light. Now the lock-nuts 41 are slightly slackened and the sleeve 44 revolved by its 45 knurled head 46 in the proper direction to raise or lower the light, as the case may be, until the accurate focus of the reflector has been reached when all the lock-nuts may be tightened and the tubular member 26 with 50 its appurtenants be securely retained in proper position.

In order to pass the tubular member 26 and its socket 27 into the reflector, I provide an opening 24 therein; and to afford exit of 55 heated air, I may provide the same with an exit-opening 37, all as clearly shown in Figs. 1 and 6.

It will now be observed that by locating the electric incandescent lamp vertically into the headlight, the vertical vibrations of a car, ship, or other vehicle or vessel will not seriously affect the filament and prevent breakage thereof.

In order to adapt this headlight for use in 65 connection with illuminating gas, I screw

upon the upper end of the tubular member 26 a collar or flange 53, shown in detail in Fig. 2, and fasten thereto a spiral spring 52 with its lower end, and secure the spring with its upper end to a cup 51 having a large opening 58, Fig. 1, in its bottom to allow the cup to swing sidewise within the radius of this opening. Into this cup 51 I place the lower end of the light-protector 36, its upper end being retained in a groove 50, formed on a tube 49, secured to the inner surface of the casing 10. To insert this light-protector 36, the lower end thereof is placed into the cup 51 by deflecting the latter, and depressing it until the upper end of the light-protector can be placed into the groove 50, when the spiral spring 52 will keep the light-protector 36 in proper position.

To carry off the gases of combustion, I place a tube 40 over the exit-opening 38 in the casing 10, and support a dome 39, above this tube by brackets 59; and in order to supply oxygen for combustion, I provide in the casing 10 a sufficient number of openings 55 through which the air may enter, and pass partly through the opening 58 in the cup 51, and also through openings 60 in the light-protector 36.

In the drawings I have shown the casing 10 in a conical contour, and I have, therefore, formed the blocks 28 and 33 wedge-shaped to coincide with the inclination of the casing. While I prefer this conical contour, I shall not confine myself exclusively to this construction, and I may make this 100 casing cylindrical and shape the blocks 28 and 33 accordingly. I have also shown the casing as being circular in cross-section; but it is evident that any other form, such as polygonal, oblong, ovoid, or other shape 105 may be given to this casing without departing from my invention; and instead of being corrugated, it may also be made plain, if so desired.

The reflector 15 heretofore described is 110 preferably made of glass and silvered on its outside so that the heat in its interior or obnoxious gases and atmospheric conditions will not tarnish the same; but I may also produce this reflector in metal in the process of drawing or spinning, and silver, or nickel-plate the same in its inside, such a change being clearly within the scope of my invention.

When the headlight is used in connection 120 with illuminating gas, I apply a hose 54 to the lower end of the tubular member 26 and conduct the gas to the burner through the bore of the said tubular member.

In the case when a diaphragm 21 is employed to sustain the rear end of the reflector, I secure it in the casing 10 by screws 17, Fig. 1, and this diaphragm as well as the front ring 18 being thus removable, the reflector may, if broken or damaged, be 130

readily removed by moving one or the other of these diaphragms.

In making the vertical adjustment of an electric incandescent lamp within the reflector, the device for accomplishing this result as shown in Fig. 2 may be employed where cheapness of manufacture is desired, but since it is open to the objection that when the tubular member is revolved the cords 36 will be twisted, which is sometimes annoying, I prefer to employ the device illustrated in Figs. 6 and 7, wherein the tubular supporting member 26 with its cords remains stationary, or non-revolving, and hence will not twist the cords, the vertical movement of the member 26 being accomplished by revolving the sleeve 44 as already described.

The casing 10 may be supported in position on a car, ship, or other vehicle or vessel in any desired manner that will not interfere with the proper functioning of the mechanism for adjusting the source of light, and since this forms no part of my present invention, I have omitted to show or describe such supporting means.

Having thus fully described my present invention, I claim as new and desire to secure to me by Letters Patent of the United States—

1. A headlight, comprising an outer, tapering, casing; a parabolic reflector removably mounted in said casing, there being an opening in said casing and said reflector; a lamp in said reflector; a vertical, tubular, member upon which said lamp is mounted; a tapering, slideable, block in said casing; a fixed, tapering, block on the outer surface of said casing and in line with the inner block, said tubular member being constructed to pass through said blocks and vertically adjustable therein.

2. A headlight, comprising a casing, a grooved ring in the forward end of said casing, a grooved diaphragm in said shell near its bottom; a parabolic reflector in said casing and having an outwardly-flaring flange engaging the groove in the said ring; means for supporting the rear end of said reflector; an opening in said reflector; a slotted aperture in the casing in vertical line with said opening in the reflector; a socket, and a tubular member to which said socket is secured; a sliding block having an internally screw-threaded passage for said tubular member; a fixed and slotted block on the outside of said casing and in line with the aperture in said casing, and lock-

nuts on the tubular member, as and for the object stated.

3. A headlight, comprising a tapering casing, a vertically disposed source of light, a screw-threaded tubular member supporting said source of light; a tapering, slideable block within said tapering casing; a fixed, tapering, block having a slotted aperture, below said slideable block, and a lock-nut on said tubular member below the fixed, slotted, block.

4. A headlight, comprising a casing; a reflector in said casing; means for removably supporting said reflector in said casing; a burner in said reflector; a light-protector surrounding said burner; a vertical tubular member upon which said light-protector is yieldingly mounted and which carries the burner at its upper end; means for horizontally and vertically adjusting the said burner, and means for receiving the upper end of said light-protector.

5. A headlight, comprising a casing, a reflector; means for sustaining said reflector removably in said casing; a source of light in said reflector; a support for said source of light comprising a tubular member, a slideable block through which said tubular member is passed, a collar on said tubular member, a spiral spring secured to said collar, a cup-shaped member secured to the other end of said spring, a light-protector resting in said cup-shaped member, and means for supporting the upper end of said light-protector.

6. In a headlight, the combination, of a parabolic reflector; a source of light in said reflector, means for locating the source of light within the focal point of said reflector; said means comprising a tubular member supporting said source of light, said tubular member being externally screw-threaded at its lower end, a locknut on this lower end, an externally screw-threaded sleeve engaging said tubular member; a slideable block having an internally screw-threaded bore engaging said sleeve; a fixed block below said slideable block and a lock-nut on the sleeve, as stated.

In testimony that I claim the foregoing as my invention I have hereunto set my hand in the presence of two subscribing witnesses.

HERON L. HILES.
